DESIGN FOR A SIGNAL LAMP

John Arcelon, Mount Vernon, N. Y.

Application March 7, 1936, Serial No. 61,519

Term of patent 14 years

To all whom it may concern:

Be it known that I, John Arcelon, a subject of the King of Italy and a resident of the city of Mount Vernon, county of Westchester, and State of New York, have invented a new, original, and ornamental Design for a Signal Lamp, of which the following is a specification, reference being had to the accompanying drawing, forming part thereof.

Fig. 1 is a front elevation of a signal lamp show-

ing my new design. The front and rear are similar in appearance.

Fig. 2 is a side elevation thereof.

The opposite side of the lamp is similar in appearance with the exception that the light is omitted.

I claim:

The ornamental design for a signal lamp as shown and described.

JOHN ARCELON.
